STEEL BRUSH ROAD DRAG

Leon J. Densberger, Hastings, Nebr.

Application October 15, 1931, Serial No. 569,037

14 Claims. (Cl. 37—143)

This invention relates to road drags, and has for one of its objects to provide a novel drag of this character which shall be adapted to smooth the rough surfaces of dirt and gravel surface roads and streets by grinding away the high and filling in the low spots of such surfaces.

The invention has for a further object to provide a drag of the character stated which shall be adapted to maintain the surfaces of oiled roads in smooth condition and which shall be adapted to be used behind an oil distributor for the purpose of spreading the oil smoothly over the surface being treated and for the purpose of preventing the splashing of the oil on automobiles.

The invention has for a further object to provide a road drag of the character stated which shall be adapted to remove the smallest irregularities from dirt race-tracks and which shall be adapted to be used after rains and heavy sprinklings to so stir up the surfaces of race-tracks as to result in the rapid drying thereof.

To attain the foregoing and other objects, the nature of which will appear as the description proceeds, the invention comprehends the provision of a road drag embodying sections made up from a plurality of brushes arranged one in advance of the other and each including groups of spring steel bristles.

The invention further comprehends the provision of a road drag of the character stated wherein the brushes of the sections thereof may be arranged to extend at a right or a lesser angle to the longitudinal axis of the road.

The invention further comprehends the provision of a road drag of the character stated wherein each brush shall embody a head consisting of upper and lower bars, wherein the bristles shall be secured to the upper bar and pass freely through the lower bar, wherein the upper bar shall be made from metal to provide a strong connection between the bristles and head, and wherein the lower bar shall be made of wood to provide a cushion for the bristles.

The invention further comprehends the provision of a road drag of the character stated wherein each section shall embody side bars and cross bars, and wherein the cross bars shall be of channel formation for the reception of the heads of the brushes.

The invention further comprehends the provision of a road drag of the character stated wherein the bristles shall be provided with angular upper end portions positioned between the heads and the cross bars and clamped therebe-

tween by the means securing the heads to the cross bars, to the end that the bristles cannot become accidentally detached from their heads.

The invention is hereinafter fully described and claimed, and illustrated in the accompanying drawings, wherein:—

Figure 1 is a top plan view of one of the sections of a road drag constructed in accordance with my invention.

Figure 2 is a view in end elevation on an enlarged scale of the road drag section.

Figure 3 is a view in side elevation on an enlarged scale of the road drag section.

Figure 4 is a sectional view on an enlarged scale taken on the vertical plane indicated by the line 4—4 of Figure 1.

Figure 5 is a sectional view taken on the horizontal plane indicated by the line 5—5 of Figure 4.

Figure 6 is a top plan view more or less diagrammatic of the road drag, and

Figure 7 is a view in side elevation of one of the brush bristles of the road drag.

The road drag comprises a plurality of sections which may be of square, oblong or other formation in plan and each of which comprises side bars 1 and cross bars 2. The side bars 1 are made of angle iron, and are arranged upon the cross bars 2 with their vertical flanges 1a extending upwardly from the outer edges of their horizontal flanges 1b. The cross bars 2 are made of channel iron with their hollow sides disposed lowermost. The cross bars 2 are secured at their ends to the horizontal flanges 1b of the side bars 1 by bolts 3, and the vertical flanges 1a of the side bars are terminally provided with clevises 4.

Brushes 5 are secured to the cross bars 2. Each brush comprises a head 6 and bristles 7. The heads 6 which are substantially equal in length to the cross bars 2, consist of upper metal bars 8 and lower wood bars 9, and are arranged within the channels of the cross bars. The side walls 10 of the channels of the cross bars 2 converge upwardly, and the sides 11 of the heads 6 also converge upwardly and contact with the side walls of the channels. The heads 6 have a wedge fit in the cross bars 2, and are held therein by bolts 12 which are also used for the purpose of drawing the heads into the cross bars.

The bristles 7 are made from oil tempered spring steels, and have their upper portions arranged in openings 13 and 14 formed in the head bars 8 and 9, respectively. These bristles 7 are so constructed that they will readily flex rearwardly upon forward movement of the brush or drag and after sliding over one projection in the roadway,

the bristles 1 will swing forwardly and in this forward swinging movement will strike subsequent projections with sufficient force to loosen or cut off these subsequent projections and then 5 push these loosened projections forwardly until a cavity is reached or until the loosened material moves between the groups of bristles. The upper end portions of the bristles 1 are bent to provide retaining elements 15 which are arranged at right 10 angles to the bristles and which are positioned and clamped between the head bars 8 and the cross bars 2. The bristles 1 are arranged in relatively spaced groups and each group consists preferably of eight bristles. The bristles of each 15 group are normally in contact and have a snug fit in the head bar openings 13 and 14, and the attaching elements 15 of the bristles are longer than the diameter of said openings. In view 20 thereof, and as the attaching elements 15 are clamped between the cross bars 2 and heads 6, the bristles 1 are positively held against accidental displacement from the heads. The metal head bars 8 add strength and rigidity to the heads, and the wood head bars 9 function as 25 cushions for the bristles 1 when the bristles are flexed as the result of their engagement with the road surface being treated.

The groups of bristles of each brush 5 are arranged in staggered relation, as shown in Figure 30 5, in order that each portion of the road surface being treated will be subjected to the action of the bristles.

The sections of the road drag are arranged in 35 sidewise relation with the vertical flanges 16 of their side bars 1 in contact and are held in such relation by certain of the clevises 4. A drag chain 16 for securing the road drag to a tractor road oil machine or the like, has a central branch 16a and side branches 16b, the central branch 40 being secured to the central front clevis 4, and the side branches being secured to the side front clevises 4. The cross bars 2 of the road drag sections may be arranged in alinement, as shown by solid lines in Figure 6, or they may be arranged in angular relation as shown by broken lines in this figure, the bolts 3 connecting the cross bars 2 to the side bars 1 in a manner to permit them to be arranged in alined or angular 45 relation. When the cross bars 2 are arranged in 50 angular relation the central branch 16a of the tractor chain 16 is omitted. If desired but one section may be employed and when but one section is employed the drag chain is connected to two of the clevises of such sections.

55 In practice, the drag is moved along the road to be smoothed with the lateral ends of the bristles 1 in contact with the surface of the road. The weight of the drag will hold the bristles in engagement with the surface of the road, with 60 the result that the surface will be subjected by the bristles to a grinding or brushing action. This causes the grinding away of the high and the filling in of the low spots of the surface. The drag is especially adapted for smoothing corduroy 65 or washboard road surfaces and for smoothing those choppy road surfaces occurring after certain periods.

Furthermore the bristles will evenly spread oil 70 over road surfaces and will when used in connection with a road oiling machine prevent the oil from splashing on automobiles. When the drag is used on a dirt race-track the bristles will remove all irregularities therefrom, and will when used after a rain or heavy sprinkling so stir up 75 the surface of the race-track as to permit it to

dry rapidly. When the drag is to be used on dirt race tracks the upper and lower bars of the brush heads will be both made of wood so as to lighten the machine for the particular work to be done.

The machine may also be used for the purpose 5 of preparing ground before seeding small grain, for smoothing and finishing the bottoms of irrigation ditches, and for dragging out roots on any weeded surface.

While I have described the principle of the invention, together with the structure which I now consider the preferred embodiment thereof, it is to be understood that the structure shown is merely illustrative and that such changes may be made, when desired, as fall within the scope 10 of the invention as claimed.

What is claimed is:—

1. A road drag including a cross bar having a channel in its underside, a head bar located in the channel of and secured to the cross bar, and 20 spring steel bristles passing through the head bar and having angular upper end portions positioned between the head bar and cross bar.

2. A road drag including a cross bar having a channel in its underside, a metal upper head bar 25 and a wood lower head bar located in the channel of and secured to the cross bar, and spring steel bristles passing through the head bars and having angular upper ends positioned between the upper head bar and the cross bar.

3. A road drag including a cross bar having a channel in its underside, a head bar located in the channel and secured to the cross bar and provided with relatively spaced openings arranged in staggered relation, and groups of closely related spring steel bristles having their upper portions snugly fitting in said openings and provided at their upper ends with angular attaching elements positioned between the head bar and cross bar.

4. A road drag including a cross bar having a channel in its underside, the channel having upwardly converging side walls, a head bar having upwardly converging sides located in and having a wedge fit in the channel of the cross bar, bolts 45 passing through the cross and head bars to secure said bars together, and spring steel bristles secured to the head bar.

5. A road drag including side bars having horizontal and vertical flanges, cross bars provided in their lower sides with channels and having their ends positioned in contact with the underside of said horizontal flanges, bolts securing the cross bars to the side bars for adjustment into right angular or a smaller angular position with 55 relation thereto, head bars secured within the channels of the cross bars, and spring steel bristles secured to the head bars.

6. A road drag including a channeled cross bar and an apertured bar secured thereto, and groups of resilient metallic bristles passing through the apertures of the head bar and having angular upper end portions positioned between the head bar and the cross bar.

7. A road drag including a cross bar and an apertured head bar secured thereto, and groups of metallic bristles passing through the apertures of the head bar and having angular upper end portions positioned between the head bar and the cross bar.

8. A road drag including a cross bar and an apertured head bar secured thereto, and groups of cylindrically arranged metallic bristles passing through the apertures of the head bar, said groups of bristles being spaced from each other 75

with their lower ends out of contact with each other and being arranged in staggered relation.

9. A road drag including a cross bar and an apertured head bar secured thereto, and groups 5 of metallic bristles passing through the apertures of the head bar, said groups of bristles being spaced from each other with their lower ends out of contact with each other and being arranged in staggered relation.

10. 10. A road drag including a cross bar and an apertured head bar secured thereto, and groups of bristles passing through the apertures of said head bar, each of said groups of bristles consisting of a solid cylindrical bundle of resilient metallic bristles each having an angular upper end portion positioned between the head bar and the cross bar.

11. A road drag including a cross bar and an apertured head bar secured thereto, and groups 20 of bristles passing through the apertures of said head bar, each of said groups of bristles consisting of a solid bundle of resilient metallic bristles each having an angular upper end portion positioned between the head bar and the cross bar.

25. 12. A road drag including a cross bar and a head bar secured thereto, and groups of bristles

passing through said head bar with the upper ends thereof abutting against said cross bar, each of said groups of bristles consisting of a solid cylindrical bundle of resilient bristles, the peripheral bristles of said bundles having outwardly and radially projecting portions.

13. A road drag including a cross bar and a head bar secured thereto, and groups of bristles passing through said head bar with the upper ends thereof abutting against said cross bar, each 10 of said groups of bristles consisting of a solid bundle of resilient bristles, the outer bristles of said bundles having outwardly and radially projecting portions.

14. A road drag for smoothing uneven road 15 surfaces comprising a cross bar, an apertured head bar secured thereto, and groups of resilient bristles seated in the apertures and depending below the head bar, each member of said bristles constituting a resilient smoothing means capable, 20 upon being flexed rearwardly by contact with a relatively fixed projection in a road and sliding over said projection, of swinging forwardly with sufficient force to cut off or loosen subsequent projections.

LEON J. DENNSBERGER.
